RAIL ANCHOR MEANS

Tom W. Saul, Tucson, Ariz.

Application December 16, 1946, Serial No. 716,508

7 Claims. (Cl. 238—321)

1

My invention relates to means commonly referred to as anti-creepers for anchoring rails to ties, or the like.

One of the principal objects of this invention is to provide a rail anchor or anti-creeper of this class which is of V-shape and which may be secured in place over a base flange of a railroad rail, by forcing the same over the outer edge of the flange, and thereby separating the jaws or legs of the V-shaped anchor so as to embrace tightly, and over their length, the opposite faces of the flange.

An important object also is to provide an anchor of this class having a stop which provides a definite limit means so as to prevent spreading of the jaws or legs of the anchor, beyond its most effective gripping action, upon the opposite sides of the flange.

Another important object of this invention is to provide simple and economical means for creating effective friction between the adjacent surfaces of the rail flange and the anchor or anti-creeper when the latter is driven or forced over the former.

Another important object of this invention is to provide means between the engaging or contacting surfaces, or portions of the rail flange and anchor, to increase the gripping action of the anchor upon the flange, by biting into the adjacent faces or portions of each, such means being in the form of a hard, sharp, granular material interposed between the adjacent surfaces of the rail flange and anchor.

A further important object of this invention is to provide a yieldable binder for locating the granular material in the desired manner between such surfaces.

A still further important object is the provision of a yieldable frictional material, which will assist in the gripping action of the jaws or legs upon the opposite sides or faces of the base flange.

Another important object of this invention is to provide an anchor of this class which is particularly simple and economical of construction, and which may be easily applied, and one which may be removed without much effort, and also one which may be reapplied or reused.

With these and other objects in view, as will appear hereinafter, I have devised a rail anchor means having certain novel features of construction, combination, and arrangement of parts and portions, as will be hereinafter described in detail and particularly set forth in the appended claims, reference being had to the accompanying drawings and to the characters of reference thereon, which form a part of this application, in which:

Fig. 1 is a perspective view of a portion of a railroad rail with my anchor in its preferred form mounted thereon;

2

Fig. 2 is an enlarged elevational view of my anchor, partly in section, shown mounted on a fragmentary portion of a base flange of the rail, the flange being also shown in section; and,

Fig. 3 is a fragmentary view of my anchor, partly in section, in a slightly modified form.

The rail 1, shown in the drawings, is of a cross-section commonly employed in railroad rails. The portions 1^a designate the base flanges which extend laterally from the rail and support the same on the railroad tie 2. The purpose of my rail anchor means A is similar to that of other anchors of this type now in use, and is mounted on one of the base flanges of the rail in such a manner as to abut one side of the tie to prevent creeping of the rail thereon.

The rail anchor means A comprises essentially an anchor member, which is substantially V-shaped, and comprises substantially straight legs 11 and 12 connected at one end by a connecting portion 13, the connecting portion is substantially circular and of approximately 220 degrees or $\frac{2}{3}$ of a circle in extent. The ends of the connecting portion 13 merge in gradual reverse curves with the legs 11 and 12.

The legs and connecting portion of the anchor member are of uniform thickness and may therefore be forged from bar stock.

The legs 11 and 12 diverge from the connecting portion 13 at an angle slightly less than the included angle between the upper and lower faces of the flange 1^a. Thus, when the anchor is driven over the outer edge of the flange, the legs, which form jaws, spread apart, so that they lie substantially parallel to the adjacent faces of the flange, and, as they are bent outwardly, they exert a clamping or gripping force upon the adjacent portions or faces of the flange. For this reason the anchor member is made slightly resilient to permit the legs or jaws to be spread and tightly to grip the flange.

The anchor member is so shaped that it may be forced over the edge of the rail flange to an extent only which prevents the spreading of the legs or jaws beyond its most effective gripping action upon the opposite sides or faces of the flange. Such limiting is effected by the engagement of a portion near the center of the connecting portion 13 with a portion of the outer edge of the flange, as indicated by 13^a in the drawings.

This limiting portion may be in the form of a segment 14, at the inner side of the connecting portion 13, which may engage the outer edge of the flange 1^a to effect a more positive stop. This stop or limiting segment 14 may be separately fabricated and secured to the inner side of the connecting portion, indicated by dash lines, or the connecting portion may be upset to this extent to provide such stop or limit means.

To facilitate the gripping action between the

adjacent faces of the legs or jaws and the faces of the flange 1^a, I have interposed a hard and sharp granular material 15 therebetween. This material may be of various forms, such as Carbide. This material may be more effectively placed between the engaging portions of the rail and anchor by affixing it to the inner sides of the legs or jaws by means of a suitable cement 16. This cement is preferably pliant and resilient.

As the anchor is forced or driven over the edge of the rail flange by means of a hammer, or the like, the hard and sharp granules 15 are imbedded or bite into the metal of both the rail and the anchor and substantially or temporarily lock the anchor in position.

The cementitious material 16, which performs the function of evenly distributing or locating the granules 15, also assists in providing a frictional joint between the rail flange and the anchor, at the portions between the granules 15.

In Fig. 3 I have shown a modified form of the means for creating or producing friction between the adjacent faces of the anchor, designated here as 21, and the flange 1^a. Such means is here shown as a shim 22 which, when in position, is of U or V-shape. When the rail and anchor are made of steel, as in conventional construction, the shim is made of friction creating material, such as cast iron.

In this modification the outer end of the anchor is also of slightly different shape, which permits the whole anchor to be of uniform thickness. This form may also be used in the first described structure.

I wish it to be understood that I do not desire to be limited to the exact details of construction shown and described, for obvious modifications will occur to a person skilled in the art.

I claim:

1. A rail anchor securable over one base flange of a rail, comprising a V-shaped resilient member having legs diverging from each other at an angle slightly less than the included angle between the opposite faces of the flange over which the member is adapted to be secured, said legs being so constructed as to be separable when forced over the flange to engage said opposite faces thereof tightly, resiliently, and flatwise, the inner side of the connecting portion between the legs providing a stop to limit the forcing of the member over the flange and thereby limit the spread of the legs to an amount insuring uniform engagement of the legs with said flange throughout their length.

2. A rail anchor securable over one base flange of a rail, comprising a V-shaped resilient member having legs diverging from each other at an angle slightly less than the included angle between the opposite faces of the flange over which the member is adapted to be secured, said legs being so constructed as to be separable when forced over the flange to engage said opposite faces thereof tightly, resiliently, and flatwise, the inner side of the connecting portion between the legs having a flat shoulder providing a stop against the outer edge of the flange to limit the forcing of the member over the flange and thereby limit the spread of the legs to an amount insuring uniform engagement of the legs with said flange throughout their length.

3. A rail anchor securable over one base flange of a rail, comprising a V-shaped resilient mem-

ber having legs connected by a circular portion of an extent of approximately 220 degrees, said legs diverging from said connecting portion at an angle slightly less than the included angle between the opposite faces of the flange over which the member is adapted to be secured, said legs being so constructed as to be separable when forced over the flange to engage said opposite faces thereof tightly, resiliently, and flatwise, the inner side of the connecting portion between the legs providing a stop to limit the forcing of the member over the flange and thereby limit the spread of the legs to an amount insuring uniform engagement of the legs with said flange throughout their length.

4. A rail anchor securable over one base flange of a rail, comprising a V-shaped resilient member having legs diverging from each other at an angle slightly less than the included angle between the opposite faces of the flange over which the member is adapted to be secured, said legs being so constructed as to be separable when forced over the flange, and a hard, sharp, granular material applied on a surface of the member capable of being positioned adjacent the corresponding face of the flange.

5. A rail anchor securable over one base flange of a rail, comprising a V-shaped resilient member having legs diverging from each other at an angle slightly less than the included angle between the opposite faces of the flange over which the member is adapted to be secured, said legs being so constructed as to be separable when forced over the flange, a hard, sharp, granular material, and a yieldable binder securing the latter to the surface of the member capable of being positioned adjacent the corresponding face of the flange.

6. In a means of the class described, the combination with a rail having base flanges, of a rail anchor secured over one base flange, said anchor comprising a V-shaped resilient anchor having legs diverging from each other, said legs being so constructed as to be separable when forced over the flange, and a hard, sharp, granular material interposed between adjacent surfaces of the flange and anchor, and capable of being imbedded in said adjacent surfaces when the anchor is forced over the flange.

7. A rail anchor securable over one base flange of a rail, comprising a V-shaped member having legs diverging from each other to fit over the opposite faces of the base flange, and a friction means applied between a face of the flange and the adjacent leg of the V-shaped member, said means comprising a hard, sharp, granular material, and a binder spacing said material, said material and binder securing the latter leg to the latter face of the flange.
